UNITED STATES PATENT OFFICE

2,482,632

DUMP GRATE MECHANISM

Donald J. Mosshart, Ardmore, Pa., assignor to
Westinghouse Electric Corporation, East Pittsburgh, Pa., a corporation of Pennsylvania

Application October 12, 1946, Serial No. 702,965

3 Claims. (Cl. 110—165)

1

This invention relates to stoker apparatus, more particularly to dump grate mechanism therefor, and has for an object to provide improved mechanism of this character.

Another object of the invention is to provide improved means for supporting and operating a dump grate structure, whereby cascading of fuel from the grate proper to the ash pit during dumping periods, is prevented and clinker formations bridging the dump grate are positively broken and dumped.

Yet another object of the invention is to provide improved linkage mechanism for moving a plurality of elements making up a dump grate mechanism.

The foregoing and other objects are effected by the invention as will be apparent from the following description and claims taken in connection with the accompanying drawings, forming a part of this application, in which:

Fig. 1 is a transverse sectional view through a stoker structure embodying the principles of the present invention, the dump grate mechanism shown at the left of this figure being in its raised or fuel-receiving position and the dump grate mechanism shown at the right being in its lowered or dumping position;

Fig. 2 is a fragmentary view of the dump grate mechanism of Fig. 1, but showing the same in intermediate position; and,

Fig. 3 is a fragmentary plan view of the dump grate mechanism, in the position shown at the left of Fig. 1.

Referring now to the drawings more in detail, the reference character 10 indicates, in its entirety, grate structure disposed in a furnace 11, whose front wall 12 is provided with openings 13 through which fuel is adapted to be fed to the grate surface by suitable mechanism of the "spreader" or "sprinkler" type, indicated at 14. The furnace may be provided with side walls 15 having headers 16 from which tubes 17 extend upwardly to overhead headers (not shown) in the usual manner.

In the construction herein shown, the grate structure 10 comprises central or apex bars 19, a plurality of intermediate bars 20, 21 and 22, and end or pusher bars 23, all of these bars being joined in end-to-end relation by pivot pins 24 and providing a fuel-supporting surface of the inverted-V type, adapted to feed the fuel laterally in both directions from the central apex. The end or pusher bars 23 have their rearward ends, considered in the direction of fuel feed thereover, supported by stationary plates 26 on which 55

2

they are adapted to slide, the plates 26 being supported by structural members 27 and 28 carried by the usual concrete side walls 29 of the plenum chamber 30.

5 The central or apex bars 19 are secured to supports 32 by pins 33, the supports 32 being fixedly secured on squared portions of a rocker shaft 34 carried by bearing structure 35 mounted on structural members 36, 37 and 38.

The first intermediate bars 20 are supported by links 40, whose lower ends are pivotally connected to brackets 41 carried by the structural members 36, and links 42 extend from points intermediate the ends of the links 40 to the free ends of upper arms 43 of bell cranks 44, mounted on shafts 45 carried by bearing structure 46. The lower arms 47 of the bell cranks 44 are connected through links 48 with the rearward ends of the second intermediate bars 21 and these links 48 15 are connected intermediate their ends with links 49, whose other ends are pivotally connected to rocker members 50, supported on bearings 51 and provided with upper rocking surfaces 52 on which rest the third intermediate bars 22.

20 It will be apparent that, in operation, oscillatory movement of the main rocker shaft 44 will cause tilting movement of the central or apex bars 19, and inasmuch as these bars are pivotally connected in series with the intermediate bars

25 20, 21 and 22 and the end bars 23, and undulatory movement will be imparted to the entire fuel-supporting surface, with the action of the bars on one side of the grate opposed to the action of the bars on the opposite side. Inasmuch as 30 the particular grate structure illustrated forms no part of the present invention, further discussion thereof is believed unnecessary except that it may be pointed out that the number of intermediate bars 20, 21 and 22 may be increased or 35 decreased depending upon the width of the stoker.

The present invention is primarily concerned with the dump grate mechanism, indicated in its entirety by the reference character 55, this mechanism including first members or grate bars 56 and second members or plates 57, considered in the direction of ash feed thereover, pivotally connected in end-to-end relation at 58. The forward ends of the first members 56 are pivoted to the stationary supporting plates 26, as at 59, 45 and the second members 57 are supported through pivotal connections 60 intermediate their ends, by links 62 whose lower ends 63 are pivoted, as at 64, to the free ends of crank arms 65, fixedly secured to dump grate shafts 67.

In operation, and considering the structure

as illustrated at the left of Fig. 1, the shaft 67 is rotated in counterclockwise direction to move the mechanism from its ash-retaining position as shown, to dumping position. During this movement, the free ends of the crankshafts 65 move downwardly and inwardly with the first members 56 stationarily supported by the curved upper surfaces of the crank arms 65. The second members 57 swing downwardly about their pivotal connections 58 with the first members 56.

When the dump grate mechanism has moved to the intermediate position shown in Fig. 2, abutments 68 at the lower ends of the links 62 engage upon projecting structures 69, provided on the structural members 28, with the result that further clockwise movement of the shaft 67 (Fig. 2) causes an upward movement of the pivotal connections 68 between the links 62 and the second dump grate members 57, with the result that the pivotal connections 58 between the two dump grate mechanisms are likewise raised until the two members 56 and 57 assume the final position shown at the right in Fig. 1. At this time, the first members 56 are inclined upwardly in the direction of ash movement thereover and serve to prevent cascading of the fuel from the grate surface to the ash pit 70, while at the same time they positively break up any refuse formations tending to bridge or obstruct the dump grates.

It will be apparent that the present invention provides a novel arrangement of two dump grate elements pivotally connected together in end-to-end relation, whereby positive dumping action is effected while at the same time undesirable loss of fuel from the grate surface is prevented.

While the invention has been shown in but one form, it will be obvious to those skilled in the art that it is not so limited, but is susceptible of various changes and modifications without departing from the spirit thereof.

What is claimed is:

1. Furnace dump grate structure comprising first and second members, considered in the direction of ash feed thereover, pivotally connected together in end-to-end relation; a fixed pivotal support for the front end of said first member; a movable support for said second member intermediate its ends; a first abutment on said movable support; a second fixed abutment; and means for moving said movable support through a predetermined path such that during the first portion of its movement the abutments are out of contact and the first member remains stationary and the second member is inclined downwardly in the direction of ash feed, and during the second portion of its movement the abutments are in contact, which moves the first member to a position inclined upwardly in the

direction of ash feed and the second member to a position of greater inclination.

2. Furnace dump grate structure comprising first and second members, considered in the direction of ash feed thereover, pivotally connected together in end-to-end relation; a fixed pivotal support for the front end of said first member; a crank arm and a link providing a movable support for said second member and said link having a bearing surface; a fixed abutment; and means for moving said movable support through a predetermined path such that during the first portion of movement the bearing surface is out of engagement with the fixed abutment, the first member remains stationary and the second member is inclined downwardly in the direction of ash feed, and during the second portion of movement the link bearing surface engages the fixed abutment, thereby changing the motion of the movable support so that the first member is inclined upwardly in the direction of ash feed and the second member is further inclined.

3. Furnace dump grate structure comprising first and second members, considered in the direction of ash feed thereover, pivotally connected together in end-to-end relation; a fixed pivotal support for the front end of said first member; a crank arm; a link pivotally connected at one end to the free end of said crank arm and at the other end to said second member, whereby said crank arm and link provide a movable support for said second member; a projection on said link; a fixed abutment; and means for imparting limited oscillatory movement to the crank arm with the link projection free of the abutment during part of the movement and in contact therewith during the remainder of the movement, said abutment being so disposed with respect to said link that during the part of the crank arm movement that the projection is free of the abutment the first member remains stationary in its normal position and during the remainder of the crank arm movement the engagement of the projection with the abutment moves said first member to a position upwardly inclined in the direction of ash feed.
